UNITED STATES PATENT OFFICE.

WILLIAM P. RUBLE, OF ESMOND, NORTH DAKOTA.

STEAM-ENGINE.

1,077,097.

Specification of Letters Patent.

Patented Oct. 28, 1913.

Application filed May 17, 1913. Serial No. 768,216.

To all whom it may concern:

Be it known that I, WILLIAM P. RUBLE, a citizen of the United States, residing at Esmond, in the county of Benson and State of North Dakota, have invented certain new and useful Improvements in Steam-Engines, of which the following is a specification.

My invention relates particularly to the valve mechanism of steam engines, and the primary object of my invention is to so construct and organize such mechanism as to avoid the friction which is incident to ordinary slide valves.

A further object of my invention is to operate the valves in such manner that they shall open and close their ports with ease and precision, and to generally improve the construction of the mechanism which controls the admission and exhaust.

20 In carrying out my invention, I employ a steam cylinder and piston of ordinary construction, and I provide the cylinder with admission and exhaust ports which are controlled by novel valve mechanism. The admission ports at the opposite ends of the cylinder are controlled by cylindrical valves which coöperate with a horizontally arranged block which is reciprocated in the main valve chest and is supported on the cylindrical valves. The block is formed with recesses at its opposite ends which receive ribs, cogs or teeth on the cylindrical valves, and through the teeth extend channels which communicate with the interior of the valves which latter are each open at one end and connect with other steam chests, in turn connected through suitable ports with the steam cylinder. These latter ports are provided with novel mechanism which is operated by the cylindrical valves when the latter are turned by the reciprocating block. Each of the cylindrical valves is mounted in a roller bearing to avoid friction, and as the valve block is reciprocated the ports in the teeth which lead to the interior of the valves are alternately opened and closed. The arrangement is such that the block as it reciprocates does not slide on the cylindrical valves but merely turns them to a limited extent about their axes and the recessed ends of the block alternately rise and fall to uncover and close the ports in the cylindrical valves in the manner hereinafter explained.

55 In the accompanying drawings:—Figure 1 shows a vertical central section through a part of a steam engine with my improved

valve mechanism applied. Fig. 2 shows a side elevation of the same, with the side plate or cover plate removed. Fig. 3 is a detail view in perspective, showing how the 60 roller bearings for the cylindrical valves are constructed. Fig. 4 shows a vertical section on the line 4—4 of Fig. 1. Fig. 5 is a perspective view of one of the cylindrical valves and shows particularly how it is connected with one of the valves controlling the admission and exhaust at one end of the cylinder. Fig. 6 is a detail view of one of the cylindrical valves and the reciprocating block, and illustrates the position of the 65 parts mentioned when the port in the cylindrical valve is opened. Fig. 7 is a similar view, showing the valve port closed. Fig. 8 is a detail view of the valve block and cylindrical valve, and indicates diagrammatically 70 the position of the parts when both ports are closed, when one of the ports is closed and the other open, and when the ports at opposite ends of the block are one open and the other closed. Fig. 9 is a detail view in perspective of one of the links employed for connecting the valve block with the cylindrical valves.

The cylinder A and piston B are of usual construction. The cylinder is provided, on 85 one side, with a casing C for the valve mechanism and steam chests. This casing may be provided with a removable cover D, connected to a steam supply pipe E and with a removable side plate F, as shown in Fig. 4. 90 The casing C is provided with a main steam chest G to which steam is admitted from the supply pipe E, and in this chest is arranged a reciprocating valve block H which is operated by the rod I, connected to any 95 suitable operating part of the engine. The block is given only a short reciprocating motion and coöperates with the hollow cylindrical valves J and K, which are mounted in recesses j, k in the casing and are supported 100 by roller bearings L which latter may be of any suitable kind but preferably consists of semi-circular frames l, carrying parallel spaced rollers l'.

Each of the cylindrical valves is connected 105 with the valve block G by means of links g of the kind shown in Fig. 9. One end of each link enters a recess g' (Fig. 5) in the valve while the other is connected in a similar way with the valve block. In this way 110 the block and valves are held together. Each of the cylindrical valves is formed with a

rib, cog or tooth α , which is curved or convex as shown and is adapted to fit a corresponding recess α' in the adjacent end of the valve block. A steam passage y leads from the outside of each tooth α to the interior of the hollow cylindrical valve, and each valve is formed with a hollow cylindrical extension of relatively small diameter (Fig. 4) which extends through a stuffing-box N and opens into a steam chest O which connects with the steam cylinder A , in the manner shown in Figs. 2 and 4.

As will be observed the chest O has a port o opening into a chamber P in the casing and this chamber communicates through a port o' with the cylinder A . These ports o, o' are controlled by valves Q which also control the ports leading to the exhaust pipes R . Each valve Q is L-shaped and when it is in position to close the exhaust port the admission port is open, and vice-versa. The valve mechanism at opposite ends of the cylinder is of the same construction, and each valve Q is connected by a yielding link connection S with an arm s on the adjacent cylindrical valve, and as the cylindrical valve is turned the valve Q connected therewith is suitably moved.

When the engine is on a center the admission ports of both valves J and K are closed by the block H , whose recessed ends at α' cover the outer ends of the channels y . But when the block is moved to the left as viewed in Fig. 1, the valves J and K are both turned to a limited extent by the block, the port of the valve K remaining closed while the port of the valve J is opened, as indicated in Fig. 1, by reason of the fact that the left-hand end of the block rises from the tooth α and uncovers the port. This movement of the valve J also depresses the valve Q (Fig. 2) and opens communication between the chamber O and the cylinder A through the ports o, o' , the exhaust port being at this time closed.

Figs. 1 and 2 show the position of the parts when steam is being admitted to the left-hand end of the cylinder. It will be observed by reference to Fig. 2 that the exhaust port at the right-hand end of the cylinder is open. When the movement to the right is completed, the movement of the valve block H is reversed, the admission port at the left-hand end of the cylinder being closed and the exhaust open, while the exhaust port at the opposite end of the cylinder is closed and steam is admitted.

It will be observed that there is very little frictional contact between the block and the cylindrical valves, the valve ports in the teeth of these valves being opened by the rising of the block away from the teeth rather than by a sliding movement over the ports, and the roller bearings afford an anti-friction mounting for the valves. It will be

also observed that the part of the valve Q which controls the admission is somewhat larger than that part which controls the exhaust and when the cylinder is being exhausted the steam pressure assists in closing the admission at o and in turning the cylindrical valve with which it is connected.

I claim as my invention:

1. The combination with a steam cylinder and a steam chest of cylindrical valves controlling ports connecting the steam cylinder with the steam chest, roller bearings in which said valves are mounted, and a reciprocating block connected with the valves and controlling ports therein communicating with the steam chest.

2. The combination with a steam cylinder and a steam chest of cylindrical valves at opposite ends of the cylinder controlling the passage of steam from the chest to the cylinder, roller bearings in which said valves are mounted, and a reciprocating block supported by the valves connected therewith to turn the valves as it reciprocates and which opens and closes communication between the interior of said valves and the steam chest.

3. The combination with a steam cylinder and a steam chest of hollow cylindrical valves interposed between the cylinder and the chest and each of which is provided with a tooth on its exterior having a passage communicating with the interior of the valve, and a reciprocating block in the steam chest having recessed opposite ends connecting with the teeth of the valves and controlling the entrance of steam therethrough.

4. The combination with a steam cylinder and a steam chest of two hollow cylindrical valves interposed between the cylinder and the chest and each of which is provided with a tooth on its exterior having a passage communicating with the interior of the valve, and a reciprocating block in the steam chest resting on the cylindrical valve and having recessed opposite ends connecting with the teeth of the valves adapted to close the entrance of steam thereto and to separate from the teeth and thus open communication between the interior of the valves and the steam chest.

5. The combination with a steam cylinder and a main steam chest of cylindrical valves at opposite ends of the cylinder controlling the passage of steam from said chest toward the cylinder, means for actuating said valves, supplementary steam chests to which steam is admitted by way of said cylindrical valves from the main steam chest, combined admission and exhaust valves interposed between said supplemental steam chests and the steam cylinder, and link connections between said combined admission and exhaust valves and the cylindrical valves.

6. The combination with a steam cylinder and a main steam chest of hollow cylindrical

valves having ports communicating with the main steam chest, means for actuating said valves, supplementary steam chests interposed between said valves and the steam cylinder, combined admission and exhaust valves interposed between said chests and the steam cylinder, and link connections between said combined valves and the cylindrical valves whereby when said cylindrical valves are actuated the combined valves are operated.

7. The combination with a steam cylinder of combined admission and exhaust valves controlling the admission of steam to the cylinder and the exhaust therefrom, a main steam chest, hollow cylindrical valves com-

municating therewith, and controlling the passage of steam therefrom, link connections between said hollow cylindrical valves and the combined admission and exhaust valves, 20 a reciprocating block in the main steam chest, and connections between said block and the cylindrical valves whereby the latter are moved to control the admission of steam to the cylinder and the exhaust therefrom. 25

In testimony whereof, I have hereunto subscribed my name.

WILLIAM P. RUBLE.
